CAR WASTEBASKET SUPPORT STRAP

James C. Fry, Wooster, Ohio, assignor to Rubbermaid Incorporated, Wooster, Ohio

Filed Nov. 13, 1972, Ser. No. 306,060

Term of patent 14 years

Int. Cl. D6—11
U.S. Cl. D12—155

FIG. 1

FIG. 3

FIG. 1 is a perspective view of a car wastebasket support strap embodying my new design and shown in position as used on the floor of a car.

FIG. 2 is a top plan view of the car wastebasket support strap in flat position.

FIG. 3 is an enlarged fragmentary sectional view thereof taken on line 3—3 of FIG. 2.

The undisclosed bottom is substantially flat and unornamented.

I claim:

The ornamental design for a car wastebasket support strap, as shown and described.
